ASH TRAY

Alvin W. Hunt, 1209-B Bay St.,
Santa Monica, Calif. 90405

Filed Oct. 12, 1971, Ser. No. 188,656

Term of patent 14 years

Int. Cl. D27—03

U.S. Cl. D85—2 H

FIG. 1 is a perspective view of the ash tray;
FIG. 2 is a plan view of FIG. 1;
FIG. 3 is a bottom plan view of the ash tray shown in FIGS. 1 and 2;

FIG. 4 is a fragmentary sectional view taken on the line 4—4 of FIG. 2; and

FIG. 5 is a fragmentary sectional view taken on the line 5—5 of FIG. 2.

I claim:

The ornamental design for an ash tray, substantially as shown.
